US00D851444S

(12) **United States Design Patent** (10) **Patent No.:** **US D851,444 S**
(45) **Date of Patent:** **** Jun. 18, 2019**

(54) **VACCUM BLENDER BASE**

(71) Applicant: **NuWave, LLC**, Libertyville, IL (US)

(72) Inventors: **Jung S. Moon**, Long Grove, IL (US);
Eunjung Huh, Grayslake, IL (US);
Byung G. Choi, Lake Villa, IL (US);
Li Xiang Jun, Foshan (CN); **Zeng Qing Ping**, Shanwei (CN)

(73) Assignee: **NUWAVE, LLC**, Libertyville, IL (US)

(**) Term: **15 Years**

(21) Appl. No.: **29/671,556**

(22) Filed: **Nov. 28, 2018**

Related U.S. Application Data

(62) Division of application No. 29/608,495, filed on Jun. 22, 2017, now Pat. No. Des. 834,878.

(57) **CLAIM**

The ornamental design for a vacuum blender base, as shown and described.

DESCRIPTION

FIG. 1 is an elevated isometric view of a vacuum blender base showing the new design;

FIG. 2 is a front view of the vacuum blender base shown in FIG. 1;

FIG. 3 is a rear view of the vacuum blender base shown in FIG. 1;

FIG. 4 is a right side view of the vacuum blender base shown in FIG. 1;

FIG. 5 is a left side view of the vacuum blender base shown in FIG. 1;

FIG. 6 is a top view of the vacuum blender base shown in FIG. 1; and,

FIG. 7 is a bottom view of the vacuum blender base shown in FIG. 1.

(Continued)

The broken lines showing of the appended figures are for purposes of illustrating environmental structures and form no part of the claimed design.

1 Claim, 7 Drawing Sheets
